UNITED STATES PATENT OFFICE.

CHARLES W. PALMER, OF CLEVELAND, OHIO.

IMPROVEMENT IN PORTFOLIOS.

Specification forming part of Letters Patent No. 140,725, dated July 8, 1873; application filed June 16, 1873.

To all whom it may concern:

Be it known that I, CHARLES W. PALMER, of Cleveland, in the county of Cuyahoga and State of Ohio, have invented a Portfolio, of which the following is a specification:

This invention relates to a portfolio for holding sheet-music, and, when placed on a piano or music-rack, is made a sheet-music rest for holding sheet-music steadily upright in place; and consists of a portfolio having at the lower end of the inside pages two narrow hinged shelves attached, which support the sheets when standing upright.

The accompanying drawing illustrates my improved portfolio.

A A represent the two sides or leaves of a portfolio. B B are two narrow strips of metal or other suitable material, (brass is the neatest, and preferable,) which are attached by hinges at the lower side of the leaves A A in such a manner that they may be turned down into a horizontal position, like that seen at

the left side, and are intended for supports for the sheet-music to stand upon. The stiff sides of the portfolio support the music, bending inward at the middle and falling over. When not in use the shelves B B are turned up and lie against the sides A A, and then the portfolio can be closed together with the sheet-music inside of it.

In this manner sheet-music may be carried about and in the portfolio, and when wanted for a music-rest is readily and quickly applicable to that use.

Having thus described my invention, I claim—

In combination with a portfolio, A A, the hinged shelves B B, substantially as shown and described, and for the purpose set forth.

CHARLES W. PALMER.
